UNITED STATES PATENT OFFICE

FREDERIC J. PETREQUIN, OF ST. GENEVIEVE, MISSOURI

APPARATUS FOR TREATING GASES

Application filed November 3, 1930. Serial No. 493,138.

This invention relates to an apparatus for treating gases, especially carbon dioxide gas, from lime kilns and the like, the general object of the invention being to provide means for drawing the gases from the tops of the kilns and passing them through a cleaner or filter to clean the same, specifically for the purpose of preparation for the manufacture of the gas into a pure solidified state, with means for automatically controlling the flow of gases through the system.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation, with parts in section, showing one manner of carrying out the invention.

Figure 2 is a top plan view of Figure 1.

Figure 3 is an enlarged sectional view showing the damper or valve means for causing the gases to either flow into the system or to escape through a discharge pipe.

Figure 4 is a section on line 4—4 of Figure 1.

In these drawings, the numeral 1 indicates a number of kilns, the tops of which are closed, as shown at 2, and each kiln is provided with a door 3 in its top through which material can be placed into the kiln. The covers are preferably water cooled. A pipe 4 connects the top part of each kiln to a fan or blower 5 and the outlet of each blower is connected with a stack 6. A pipe 7 connects each stack intermediate the end of the stack to a pipe 8 which extends horizontally and receives the gases from all the kilns. A damper 9 is arranged in each stack and a lever 10 is connected with the stem of each damper and a cable 11 is connected to each end of the lever. Handles 12 are connected with the lower ends of the cables. Thus the

damper can be moved to a position where all the gases will escape through the stack or it can be moved to a position where some or all of the gases will flow through the pipe 7 into the pipe 8. The gases flowing into pipe 8 are drawn into a blower 13 after passing through a relief chamber 14 which is provided with a stack 15. A damper 16 is placed in the stack and has a pulley 17 connected with its stem. A cable 18 passes over the pulley and has one end connected to a spring 19 and a weight 20 is attached to the other end of the cable. This arrangement provides a gravity balanced damper which permits excess gases to escape through the stack 15, the damper exercising uniform resistance, regardless of its natural gravitational center, by means of the spring.

The blower 13 discharges the gases into a cylinder 21 through the top of which a hollow shaft 22 passes, said shaft being rotated from any suitable source of power by the means shown generally at 23. Water or other liquid is fed into the shaft from a suitable source of supply through a pipe 24 and perforated members 25 radiate from the shaft and have their interiors in communication with the shaft so that the water or other liquid will be sprayed from said members during the rotary movement thereof. Blades 26 also radiate from the shaft and rotate therewith for causing the sprayed liquid to thoroughly act on the gases to clean the same. The solids and other impurities pass from the cylinder through the overflow pipe 27. The purified gases are taken from the cylinder through the pipe 28 which communicates with the top of the cylinder.

A valve 29 is arranged in the pipe 8 between the chamber 14 and the blower and a sprocket 30 is connected with the stem of the valve. A shaft 31 is journaled in a support 32 and carries a sprocket 33. A chain 34 passes over the sprockets 30 and 33 and a weighted lever 35 is connected with the shaft 31. An oil bell 36 is placed at each side of the upright 32 and the top portions of these bells are connected with the lever 35. A pipe 37 connects the pipe 28 to one of the bells and a by-pass 38 has its ends connected with 100

the pipe 8 above and below the valve 29. This by-pass is connected by a pipe 39 with the other bell. Valves 40 are arranged in the ends of the by-pass. Thus excess pressure in pipe 28 will raise the top part of the bell 36, which is in communication with the pipe 28, so that the lever 35 will be tilted, and this movement of the lever will be communicated by the chain and sprockets to the valve 29 so as to reduce the flow of gases passing into the filter cylinder. Likewise, both back pressure and vacuum in pipe 8 will operate the other bell to provide an even pressure in the filter cylinder. Of course, the valves 40 must be properly adjusted to permit the back pressure and vacuum in pipe 8 to properly act on the valve operating means.

The operation of the apparatus is as follows:—

20 The upper valve 40 is always wide open while the lower valve 40 is generally closed, except at times when it is desired that the operation of the two pressure cylinders 36—36 should not be. In this case, the lower valve 40 is opened slightly or "cracked" which allows part of the pressure to escape into the lower portion of the stack 8. The adjusting of the weight upon the arm 35 to the left should be far enough so that it will exert 25 enough leverage to balance the pressure in the left-hand cylinder 36. There should be a balancing action between the pressure in the upper valve 40 and the left-hand cylinder at the time when the valve 29 is wide open so 30 that the right-hand cylinder is inoperative until the pressure in the pipe 28 becomes excessive, at which time the thrust from the right-hand cylinder 36 will close the valve 29. The pipes 37 and 39 enter the cylinders 36—36 35 and extend up therein. These cylinders are filled with heavy oil while the inverted cans being hollow act as plungers and slide easily inside the outer cylinders. This makes a very sensitive arrangement sufficiently strong 40 to operate the valve 29.

What I claim is:

Apparatus for treating gas comprising a pipe and suction fan, a by-pass pipe mounted upon said pipe, a cylinder connected with the 40 discharge end of the fan, a washer operating in the cylinder, an outlet pipe connected with the cylinder above the washer, a pair of oil bells, one being connected with the last mentioned pipe and the other connected with said 45 by-pass pipe, a valve located in the first mentioned pipe between the ends of the by-pass pipe, a lever operatively connected with the oil bells and means operatively connecting said lever with said valve.

60 In testimony whereof I affix my signature.

FREDERIC J. PETREQUIN.
